ASSEMBLY PRESS

George R. Eckstein, Fairfield, Conn., assignor to
Remington Arms Company, Inc., Bridgeport,
Conn., a corporation of Delaware

Application December 14, 1950, Serial No. 201,278

9 Claims. (Cl. 86—10)

1

This invention relates to an improved press and has particular reference to a press for assembling ammunition components or other small articles including several parts. The specific embodiment illustrated is arranged for assembling primers for small arms ammunition.

Operations of this character are usually carried out in multi-station dial or straight line transfer presses which are of relatively heavy and complicated construction with large floor space requirements. Such presses have considerable inertia and may not be instantly stopped in the event of a malfunction or misfeed, which is dangerous when explosive components are being assembled. Further, no transfer machine ever developed could be certain to have perfect alignment at all operating stations under production working conditions.

It is an object of my invention to provide a small light weight press capable of safely and efficiently performing operations which would require the equivalent of a dial press having four or more stations.

It is also an object of this invention to provide a variable stroke press in which several operations may be performed in each of several different but axially aligned locations. By axially aligning the working stations and the guides for the working parts, perfect alignment in all working positions is readily achieved.

A further object, closely connected with the general objective of safe operation, is the provision of a press in which the ultimate force exerted may be readily and accurately controlled.

The exact nature of the invention as well as other objects and advantages thereof will become more apparent from consideration of the following specification referring to the attached drawings, in which:

Fig. 1 is a front perspective view of a machine embodying my invention.

Fig. 2 is a rear perspective view of the same machine.

Fig. 3 is a vertical sectional view taken through a plane indicated at 3—3 on Fig. 4.

Fig. 4 is a vertical sectional view taken in a plane at right angles to that illustrated in Fig. 3 and indicated thereon as 4—4. The mechanism is at top dead center position.

Fig. 5 is a view similar to Fig. 4 with the mechanism shown in the position occupied at the bottom of the first working stroke.

Fig. 6 is a view similar to Figs. 4 and 5, with the mechanism in the position occupied at the bottom of the second working stroke.

2

Fig. 7 is a view similar to Figs. 4, 5, and 6, with the mechanism in the position occupied at the bottom of the third working stroke.

Fig. 8 is a partial horizontal sectional view on the line 8—8 of Figs. 3 and 4.

Fig. 9 is a cam diagram illustrating the sequence of the various operations.

GENERAL DESCRIPTION

10 Referring to the drawings by characters of reference, it may be seen that I have provided a base 10 which supports a pair of pillars 11 and a cross-bar 12, this assembly comprising a main frame for the machine. Supported between the cross-bar 12 and the base 10 are a pair of columns 13 upon which there are guided for colinear reciprocation a press gate 14 carrying a punch 15, an upper die plate 16, and a lower die plate 17. A symmetrical toggle assembly comprising a pair of oppositely broken toggle joints each including the substantially identical arms 18 joins the upper end of the frame to the gate 14 and is provided with thrust plates 19 at opposed knees of the toggle assembly. Mounted on one of the thrust plates is the double-acting pneumatic cylinder 20 provided with a piston rod 21 secured to the other thrust plate. Obviously, the operation of the air cylinder in one direction will draw the knees of the toggle closer to each other and thereby move the gate 14 downwardly while reverse operation of the air cylinder will have the effect of raising the gate. During the reciprocation of the gate, the punch is brought into engagement with the work in the dies and the die plates are reciprocated into contact with each other and with other tools to be more specifically described later.

Supported across the front of the machine is an endless feed belt 22 carried on suitable rollers 40 23 and 24. This belt is intermittently driven in one direction by a gripper 25 associated with the roller 23 and operated against a return spring 26 by an air cylinder 27. A clutch 28 mounted on the frame prevents retrograde movement of the belt. Trays 29 are mounted in alignment with each run of the feed belt, permitting a component to be fed from top tray 29 onto the top run of the belt and carried thereby through track 30 into position to be fed to the die in the upper die plate. Similarly, components from bottom tray 29 may be pushed onto the lower run of the belt and carried thereby through track 31 into position to be fed to the lower die plate. The feed fingers 32 and 33 are both supported on a block 55 34 mounted for reciprocation and normally held

in a retracted position by an air cylinder 35 working against the feed spring 36.

Each of the air cylinders so far referred to, as well as one to be yet described, are driven by compressed air supplied from any suitable line through a pressure regulator 37 and dual valves 38, 39, and 40, each valve section being controlled by a separate cam 41 on cam shaft 42. This cam shaft is driven by a small motor 43 at a speed suitable to the desired cyclic rate of the machine, one revolution of the cam shaft producing one complete cycle of machine operation. Each air cylinder is actuated in turn, as shown in the diagram of Fig. 9, to perform all of the necessary operations in accurately timed sequence. Obviously, the initial selection of the cross-sectional area of the pistons and the adjustment of the regulator determines the total force available for any given cylinder.

DETAILED DESCRIPTION

Upper die plate

The upper die plate 16 is provided with a pair of guide bushings 43 slidable on the columns 13 and with a pair of return springs 45 acting to hold the die plate in an uppermost position. The exact location of this uppermost position is controlled by stop blocks 46 secured to the frame and cooperating with studs 47 in the die plate. A die support block 48 is received in a centrally disposed bore in the die plate and is itself counterbored on the lower face to provide a die receiving recess. The upper die 49 mounts in the recess and the die and die support block are both secured to the die plate by a pair of clamps 50. An aperture 51 of rectangular cross-section radially intersects the central bore 52 of the die and provides a feed passage through which a component may be fed from the upper run of the feed belt 22 by the upper feed finger 32. In the specific example shown, the units being assembled are ammunition primers of the type shown in my copending application, Serial No. 162,355, filed May 16, 1950. The primer retaining cups may be placed conical end up on the upper feed tray 29, from which they may be manually pushed onto the upper run of the feed belt and carried single file down the track 30 by the intermittent advance of the feed belt. Opposite the left hand edge of the aperture 51 the feed track terminates against a solid stop 38a, and the feed finger 32 being positioned in opposition to the aperture as it advances strips off the foremost component from the track and places it in the upper die in alignment with the axial bore therein. At the same time, the advancing feed finger block 34 carries a pair of stop blocks 53 beneath the lugs 54 on the upper die plate and over stationary bars 55 associated with the main frame. As shown in the sequence diagram Fig. 9, as soon as the feed finger has been advanced, the press gate 14 and punch 15 are moved downwardly, the punch engaging the primer retainer cup and seating it in the die bore 52. This action takes place because the die plate is held against descending by the stop blocks and the cup is not pushed entirely through the die because the punch 15 stops when the press gate contacts the upper face of the then stationary upper die block.

Lower die plate

The lower die plate 11 is, like the upper die plate, provided with a pair of guide bushings 44 slidable on the columns 13. Also, like the upper die plate, the lower plate is provided with a pair

of return springs 45, always tending to raise the die plate to a position determined by stop blocks 56 which may be formed on the same members providing the stop blocks 46.

The lower die plate is also provided with a centrally disposed aperture in alignment with that in the upper die plate and with the punch. In this aperture, against the upper face of the lower die plate, I have provided a die support block 57 counterbored in its upper face to receive a die 58. The die and die support block are retained on the plate by a pair of clamps 59 bolted to the die plate.

The lower die is provided with a radial aperture 60 leading into the central bore 61. The stop block 56, above referred to, is so dimensioned as to position the aperture 60 in opposition to the terminus of the track 31 along the upper surface of the lower run of the feed belt 22 and in alignment with the lower feed finger 33. When the feed finger moves in, the end component in the track is fed into the central bore in the die, the particular component in this instance being the primer and anvil assembly entering into the primer disclosed in my afore-mentioned copending application.

The lower die support block 57 is also axially bored at 62 and in this bore receives a primer support punch 63 provided with a holder 64 and tension spring 65. The spring is engaged between a groove 66 on the die support block and a similar groove 67 in the punch holder 64, acting always to urge the primer support punch to its uppermost position in the die support block. In the uppermost position of the lower die plate, the upper end of the primer support punch is maintained flush with the lower edge of the aperture 60 by a punch positioning yoke 68 secured to the base-plate of the machine and engaging the head of the support punch holder 64.

During the first and second working strokes of the press gate, the primer support punch is prevented from partaking in any downward movement of the lower die block by the bar 69 positioned between the head of the punch holder and the machine base. This bar 69 is reciprocable by means which will be discussed in connection with the crimping die and may be positioned to allow the head of the holder to descend to the base of the machine.

As previously pointed out, during the first working stroke the press gate and punch descend against the then stationary upper die plate and position the primer retainer therein. During the second working stroke the upper die plate is not supported, the stop blocks 54 having been withdrawn with the feed fingers, and the upper die moves into contact with the upper face of the lower die and carries the lower die plate down with it. As the lower die plate is forced down, the holder 64 stops against the bar 69 and the primer in the lower die remains stationary on the end of the punch while the upper die and the primer retainer cup are pushed down over it. When the upper die plate returns to its uppermost position, the assembled but uncrimped primer and retainer remain in the upper die which has a close fit on the retainer side walls.

Crimping die

A block 70 provided with a pair of slide rods 71 is mounted on the upper face of the lower die plate, to the rear of the die. On these rods a slide 72 is received and urged toward the die plate by springs 73, while an air cylinder 74 is

carried on the slide and has a piston rod which is extensible in the direction of the block 70 to retract the slide when air pressure is applied thereto. The crimping die holder 75 is a bar of rectangular cross-section mounted on the slide 72 in opposition to the space between the faces of the upper and lower dies when both die plates are in the positions shown in Figs. 3 and 4. Seated in a counterbore in the crimping die holder is a crimping die 76 adapted to crimp or turn in the edge of the primer retaining cup when the edge is forced into the die cavity. This die is positioned in the die holder to be coaxial with the upper and lower dies when the slide 72 is drawn to its innermost position by the springs 73.

A stem 77 extends downwardly from the block 72 and has a telescoping engagement with a tube 78 attached to the bar 69 previously referred to as providing a support for the bottom or primer support punch 63. A hole 79 in the bar 69 is positioned beneath the punch when the bar is moved inwardly with the block 72 permitting the punch to be carried down with the lower die plate.

Obviously, the descent of the press gate 14, when the crimping die is in operative position, will pick up the upper die plate and through the crimping die apply force to the lower die, carrying it downwardly until the stops 80 contact the machine base. At this point further motion of the crimping die is positively stopped and the full force of the air cylinder and toggle will be applied to the purpose of crimping the assembly between the end of the top punch 65 and the crimping die. Great force is available, for the toggle assembly may be designed to be nearly straight at this point and thus exert a considerably greater thrust than applied directly by the air cylinder.

SUMMARY OF OPERATION

Assuming that the operating cycle starts when air pressure is applied to the cylinder 27, the feed belt advances by an increment slightly greater than the diameter of the components to be assembled, thus positioning, in our example, a primer retainer against the stop in the upper track 30 and a primer against the stop in the lower track 31.

After about 25 degrees of rotation of the cam shaft 42, the appropriate valve may be opened to disconnect air cylinder 35 from pressure and permit it to exhaust to atmosphere. As this cylinder exhausts, the springs 36 draw in the block 34, carrying in the feed fingers 32 and 33 as well as the stop blocks 53. The feed fingers each carry a component from the feed track through the radial opening in the appropriate die and position it therein in alignment with the axial die bore.

Shortly after the components are fed into the dies, pressure is applied to the front side of the piston on the cylinder 20 and the back end of the cylinder is permitted to exhaust to atmosphere, thus lowering the press gate in its first stroke.

As the punch descends, the upper die plate is supported by the stop blocks 53 and the punch carries the primer retainer from a position in alignment with the radial passage in the die down into the axial bore. As the retainer enters the axial bore, it pushes ahead of it the primer assembled and crimped in the preceding cycle. The ejected unit falls into a chute 81 carried by the feed finger block 34 into the space beneath the upper die.

Sometime after the advance of the feed fingers,

the pressure may be released from the belt feed cylinder 27, permitting the spring 26 to return the gripper 25 to its neutral position. The drag of the gripper 25 over the belt does not produce a retrograde movement of the belt because of the holding action of the clutch 28. Conveniently, this retraction of the belt feed pawl may take place during the first working stroke of the punch.

It may be noted that the first working stroke is relatively short and that during this stroke the toggle assembly is so extended as to have a relatively poor mechanical advantage. This condition is tolerable and, in fact, desirable, since relatively little force is normally required to eject the previously completed assembly and insert the new retainer. In the event of a machine jam of any kind, sufficient force is not available to crush and possibly explode the assembled primer. It will be obvious that the air cylinder is not constrained to complete any given length of stroke but simply applies a resilient force tending to move the gate until the air is cut off. This is in marked contrast to a crank or other mechanical press which must complete a fixed stroke and which usually has enough inertia to convert a jam into a tool smash-up.

After an allowance of about thirty degrees of camshaft rotation for the first working stroke, air is applied to the back end of the cylinder 20 while the front end exhausts, thus raising the press gate. Simultaneously, or slightly before the lifting of the top punch, air is applied to the cylinder 35 to retract the feed finger assembly. Preferably, considerable pressure should be available in the cylinder 35 at the time the press gate actually lifts to result in a snap retraction of the feed fingers and the delivery chute when the stop blocks are released. Such a snap retraction is desirable, because the impulse imparted to the ejected primer just previously deposited in the delivery chute is sufficient to insure that primers will not pile up in the end of the chute.

The press gate having returned to top dead center and the feed finger assembly returned to its outer position, the next operation is the second working stroke of the press. During this second working stroke, the press gate and punch descend, picking up the top die plate and backing up the retainer therein with the end of the hollow punch. The top die then contacts the upper face of the lower die, carrying the lower die downward while the primer support punch carried by the lower die is able to move only a short distance before it is stopped by impingement upon the bar 69. Thereafter, the lower die is forced down over the primer support punch and the primer which has been at rest upon the end of the punch is forced into the retainer held in the upper die. Downward movement of the units of the press ceases when the toggle reaches its completely collapsed position, the end position of the primer being determined by the adjustment of the primer support punch in the holder 64. Upon the reversal of the valve connections to the cylinder 20, the press gate returns to its uppermost position, the two die plates being returned by the springs 45 to their normal positions.

The completion of a good crimp is, to a considerable extent, dependent upon having a clean crimping die and shortly before the crimping die is moved into active position, air is released through tube 82 to blow off any fragments of metal or other material which may have lodged

in the die. Simultaneously, air is also released through tube 23 to clear the dies and the ends of the feed track.

The release of air pressure in cylinder 14 permits the springs 13 to draw the crimping die into place between the upper and lower dies. Simultaneously, the bar 69 is moved inwardly to position the hole 79 beneath the end of the primer support punch.

When the crimping die is in place, the connections to air cylinder 20 are again reversed to move the press gate down for the third and final stroke of the cycle. During this stroke, the assembled primer and retainer are confined in the upper die between the punch 15 and the crimping die 16. The crimping die is supported on the lower die and forms a rigid stop for the upper die and punch when the blocks 80 stop the lower die by contact with the press bed. The edge of the retainer is forced into the crimping die and turned thereby into snug engagement with the peripheral portion of the base of the primer cup. Since the top punch is matched to the contour of the conical end of the retainer, there will be no distortion thereof. In the remote event of an explosion during crimping, the punch 15 is hollow and vents the gases to open air. The reversal of the air valves to the cylinder 20 again raises the press gate and, as before, the die plates are returned by the springs 45. At this point, the assembled and crimped primer and retainer are held in the upper die from which they will be ejected by the seating of the retainer in the early part of the following cycle.

Following the return of the punch and die plates to their upper positions, the dies may be blown out again and air pressure should again be applied to the cylinder 14 to retract the crimping die and the bar 69. This completes one cycle of machine operation which has included three working strokes of the punch to assemble, crimp, and eject the final product.

Although I have illustrated my invention by quite specific reference to one embodiment thereof, it should be realized that the machine may be applied to the assembly of other articles requiring physically different but functionally equivalent tooling. Accordingly, I intend that my invention shall be considered to be limited only by the scope of the claims appended hereto.

I claim:

1. In a machine for the assembly of a plurality of components, the combination comprising a reciprocable punch holder; a punch in said holder; a plurality of dies coaxially reciprocable with said punch; means to feed components to be assembled to said dies; a support punch mounted beneath and in coaxial alignment with said dies; and means to reciprocate said reciprocable punch into one of said dies and by engagement of the punch holder therewith to move said dies into engagement with each other and into telescoping relation over said support punch whereby components fed to said dies will be guided into each other by said dies and assembled between said reciprocating punch and said support punch.

2. In the combination described in claim 1, means associated with the component feeding means to temporarily block reciprocation of the die nearest said reciprocable punch holder as a component is fed to said die; and interengaging means on said blocked die and said punch holder to block further reciprocation of said punch when said die is blocked.

3. In a machine for the assembly of a plu-

rality of components into a unitary article, the combination comprising a reciprocable punch holder; a punch in said holder; an upper die holder reciprocable in axial alignment with the punch holder; a work-holding die in said upper die holder coaxial with said punch; means to feed a component into the die in said upper holder into alignment with said punch; yieldable power means acting to reciprocate said punch holder in a first working stroke into contact with said die holder whereby said punch is moved into but not through said die; and removable stop means positioned to prevent substantial reciprocation of said die holder while said punch holder reciprocates to seat said component more deeply in said die and to thereby eject a previously seated component.

4. In the combination described in claim 3, a lower die holder also reciprocable in axial alignment with the punch holder and spaced downwardly from said upper die holder; a component receiving die in said lower die holder coaxial with said upper work-holding die; means to feed a component into said receiving die; a support punch mounted on said lower die holder beneath the component in said receiving die; a movable bar arranged to prevent substantial downward reciprocation of said support punch; means to remove said removable upper die holder stop means; and means to reciprocate said punch holder into contact with said upper die in a second working stroke and thereby to reciprocate said upper and lower dies into contact with each other and into telescoped relation over said support punch whereby said components will be assembled in said upper work-holding die between said first-mentioned punch and the support punch.

5. In the combination described in claim 4, an assembly shaping die mounted on the lower die holder and laterally movable into the space between the work-holding die and the component receiving die; means to simultaneously move in said shaping die and to remove said movable bar; and means to reciprocate said punch holder in a third working stroke into contact with said upper die holder and thereby to reciprocate said work-holding die and the assembled components therein into contact with said shaping die to shape the assembly between said punch and the said shaping die.

6. In a press, the combination comprising a frame; a reciprocably mounted tool-holder; a pair of oppositely broken toggle joints having corresponding arms of equal length, each joint being connected at one end to said frame and connected at the opposite end to said tool-holder; a fluid pressure cylinder attached to the knee of one of said toggle joints; a double acting piston in said cylinder attached to the knee of the other of said toggle joints; reversing valve means connecting the ends of said cylinder interchangeably to exhaust and to a supply of fluid pressure; a driven cam shaft; cam means on said shaft; and valve actuators riding on said cams and operatively connected to said valve means, said actuators being arranged to actuate said valve means to interchange the application of pressure to said cylinder and to straighten and bend said toggle joints in predetermined time sequence.

7. In a press, the combination with that described in claim 6 of a punch in said tool-holder; die plates supporting at least one work-holding die in axial alignment with said punch arranged

to be positioned in a plurality of locations spaced from each other along the axis of alignment of said punch and die; and means to temporarily stop one of said die plates in one of said spaced positions during at least a portion of the time required by said toggle joint to perform one cycle of extension and retraction.

8. In a press, the combination with that described in claim 7 of spring means acting to engage said temporary die plate stopping means with the die plate; a fluid pressure cylinder associated with said plate stopping means and provided with a piston arranged to disengage said die plate stopping means against the urging of said spring; reversible valve means to connect said cylinder to a supply of fluid pressure; and additional cam means on said shaft arranged to control said reversible valve means to engage and disengage said stopping means in predetermined sequential relation to the extension and retraction of said toggle joint.

9. In a press, the combination with that described in claim 8 of die means mounted for lateral movement into alignment with said punch and with said work-holding dies; spring means urging said die means to move into said

5 alignment; fluid pressure cylinder means associated with said die means and provided with a piston arranged to retract said die means against the urging of the spring; valve means arranged to interchangeably connect said cylinder to exhaust or to a source of fluid pressure; and additional cam means on said cam shaft arranged to actuate said valve means to shift said die means in predetermined timed sequence to the operation of said toggle joint.
